(57) **CLAIM**

The ornamental design for a portion of a display screen with an animated graphical user interface, as shown and described.

DESCRIPTION

FIG. 1 is a front view of a first image of a first embodiment of a portion of a display screen with an animated graphical user interface showing my new design;

FIG. 2 is a front view of a second image thereof;

FIG. 3 is a front view of a third image thereof;

FIG. 4 is a front view of a first image of a second embodiment of a portion of a display screen with an animated graphical user interface showing my new design;

FIG. 5 is a front view of a second image thereof; and

FIG. 6 is a front view of a third image thereof.

In the first embodiment, the appearance of the transitional image sequentially transitions between the images shown in FIGS. 1 through 3. In the second embodiment, the appearance of the transitional image sequentially transitions between the images shown in FIGS. 4 through 6. The process or period in which one image transitions to another image forms no part of the claimed design. The broken line showing of a portion of a display screen in FIGS. 1 through 6 forms no part of the claimed design. The broken line showing of text and portions of the graphical user interface in FIGS. 1 through 6 represents environmental subject matter and forms no part of the claimed design.

In FIGS. 5 and 6, the greyscale fill appearing on the portion of the slider bar to the left of the slider icon represents a contrasting appearance from the interior of the portion of the slider bar to the right of the slider icon.
